GILBERT W. GOODRIDGE, OF FAIRFIELD, CONNECTICUT, ASSIGNOR TO THE BRYANT ELECTRIC COMPANY, OF BRIDGEPORT, CONNECTICUT, A CORPORATION OF CONNECTICUT

ATTACHMENT PLUG AND RECEPTACLE

Application filed March 16, 1925. Serial No. 16,008.

My invention relates to an attachment plug and a receptacle therefor. The object of my invention is to provide a plug and a receptacle therefor, both of simple and rugged construction, the conductors of which are protected against mechanical injury, while those of the receptacle are so housed that accidental contact therewith is practically impossible.

In the accompanying drawings—

Fig. 1 is a plan view of a duplex receptacle in which my invention is embodied in one form, and showing an associated plug inserted in one of the receptacle chambers;

Fig. 2 is a section on the line 2—2, Fig. 1;

Fig. 3 is a section on the line 3—3, Fig. 2;

Fig. 4 is an inverted plan of the insulating base of the receptacle;

Fig. 5 is a central section through the plug alone;

Fig. 6 is a section on the line 6—6, Fig. 7, with the parts assembled; and

Fig. 7 is an exploded view of the plug elements.

My invention is illustrated in a duplex receptacle of the flush type, but it will be understood that many of the features of novelty may be embodied in single receptacles or multiple receptacles affording more than two outlets. It is also to be understood that the invention is applicable to receptacles other than the flush type shown, although certain features of improvement are particularly desirable in and applicable only to installations of this type.

The receptacle body is illustrated as a one-piece insulating block 15 channeled on its opposite sides at 16 and 17 (Fig. 1) to accommodate lead wires by which connection is made to the binding terminals 18 and 19 seated respectively on the depressed ledges 20 and 21 to which the channels open. The wire terminals are held in position on the ledges by screw bolts 22 and 23 (Fig. 4) which pass through the insulating base from below and electrically connect the respective wire terminals with the straps 24 and 25 let into the lower face of the base. For a duplex receptacle of the present type, each

strap is provided with a pair of receptacle contacts 26 and 27, which may be integral therewith or secured thereto in any appropriate fashion, as by rivets 28. The strap 25 extends substantially the length of the base and inasmuch as the contacts 27 are at opposite ends of the strap, it is desirable to support the latter by screws 29 (Figs. 2 and 3) adjacent its opposite ends as well as by the screw bolt 23 (Fig. 4).

To receive and house the several contacts 26 and 27 of a duplex receptacle of the character shown, the base 15 is appropriately apertured from below to form at its opposite ends contact chambers 30 for the contacts 27, and intermediate chambers 31 for the contacts 26. The two chambers 31 are adjacent but completely separated by the intervening diaphragm 32 of the base, while between each pair of chambers 30 and 31 on opposite sides of the diaphragm 32 the base is recessed from its upper face to afford a well 33 for the accommodation of the entering end of a cooperating attachment plug. The latter carries blades for engagement with the contacts 26 and 27 of opposite polarity which lie on opposite sides of the well 33. To permit the plug blades to enter the chambers 30 and 31, a slot 34 opens through the top wall of each chamber 30, 31, and continues downward at 35 in each side wall of the well 33, into which the plug enters. In the form shown the slot 35 in the side of each chamber 30 and 31 is narrow in its upper portion, but of the full width of the chamber in its lower portion. It is obvious, however, that if preferred, the width of the upper portion of the slot 35 may be maintained throughout its depth. The contacts 26 and 27 are thus housed in their respective chambers 30 and 31, and access to the same can be had only through the slots 34 and 35. It is thus practically impossible to touch the contacts by inserting the finger into the receptacle. Accidental injury in this fashion is made impossible.

The receptacle may be supported in a standard outlet box (not shown) by V-shaped end brackets 36 and 37 secured at opposite ends of the base.

ends of the block 15 and having at the apices of the brackets offset lugs 38, apertured at 39 to receive the screw bolts which take into the supporting ears of the outlet box in well understood fashion.

5 For a flush receptacle of the duplex type shown, the cover plate 40 is provided with a pair of apertures 41, (Fig. 1) through each of which the entering end of a cooperating attachment plug may be passed to bring its 10 blades into engagement with the receptacle contacts. Each of these openings is closed by a door comprising a pair of inwardly opening leaves 42 and 43, the meeting edges of 15 which extend in a direction parallel to the longitudinal mid-plane of the plate. The details of the door construction and mounting form no portion of my invention. It suffices to point out that on three sides each leaf is sheared to precise conformity with the margins of the opening 41 in the face plate. On 20 its fourth side, viz. the margin adjacent that of the cooperating leaf, an inwardly offset flange 44 is provided. The ends of this flange 25 extend beyond the opposite ends of the leaf and are bent toward each other and carried beyond the opposite margins of the leaf to form hinge arms 45 and 46. The portions 30 of the hinge arms adjacent the flange 44, and extending beyond the end margins of the door opening 41, abut against the inner face of the plate 40 and thus form stops limiting the outward movement of the leaves. The 35 free ends of the hinge arms 45 and 46 are pierced to receive a longitudinally extending hinge pin 47 common to the corresponding leaves of each door (see Fig. 2). Between the arms 45 and 46 a coil spring 48 is arranged on the hinge pin 47, one end of the spring being extended to bear against the face plate, and its opposite end bearing against the leaf and tending constantly to press the latter to closed position. The face plate is secured to the offset lugs 38 of the brackets 36 and 41 by means of the usual screws 49.

Cooperating with the receptacle structure described is the attachment plug shown in section and in detail in Figs. 5, 6 and 7. The plug comprises a pair of complementary insulating blocks 50 and 51 of precisely identical shape and therefore produced from a single die. The blocks are recessed in their juxtaposed faces to form a wiring chamber 52 in the head of the plug, to which open lateral cable entry passages 53. When formed, both passages 53 are closed by knock-out diaphragms 54, either or both of which may be subsequently removed to admit the wires to the chamber 52. Extending from the 58 chamber 52 are spaced channels 55 and 56 for the accommodation of the flat contact blades 57 and 58. At one end the blades are offset to form binding lugs 59 which project into and overlie the floor of the chamber 52. Shallow wells 60 accommodate the shanks of

the binding screws 61. Recesses 62 intermediate the ends of the channels 55 and 56 accommodate the bosses 63 punched from the contact blades and serving to hold the latter against displacement. Registering holes 64 and 65 formed in the barrier ribs 66 which cooperate to separate the channels 55 and 56, accommodate the screw bolts 67 by which the blocks 50 and 51 are united.

Each blade 57, 58, is shouldered at 68 and the contact engaging end thereof beyond the shoulder is of greater width than the shank extending to the binding terminals. To expose the side margins of the blades for engagement with the receptacle contacts, the opposite sides of the entering end of the plug body are cut away at 69, thus intersecting the channels 55—56 at the entering end of the plug, while still housing and mechanically supporting the blades at their inner margins. The shouldering of the insulating body of the plug thus forms a nose 70 at its entering end from which laterally project the edges of the blades beyond their shoulders 68. The ends of the channels 55 and 56 are closed at 71, and the outer faces 72 of the nose 70 are rounded. The entering end or nose of the plug is thus closed and shaped to facilitate its passage through the aperture 41 of the cover plate and its entry into the well 33 of the receptacle body. The mouth 73 of the well 33 and the slots 34 are beveled to guide the entering end of the plug and its blades into proper position in the receptacle.

The operation of the device is obvious. Upon insertion of a plug, its nose 70 engages the leaves 42, 43 of one of the cover plate doors and forces the latter inward and apart against the action of their springs 48. Sufficient clearance for the accommodation of the door leaves on their inward swing is afforded by the spacing of the receptacle body 15 from the face plate by the brackets 37. As the plug is further inserted the nose enters the well 33 in the receptacle body and the plug blades 57 and 58 enter the slots 34 in the top of contact chambers 30 and 31. As the plug is pushed home the exposed ends and side margins of the blades pass downward into the contact chambers and each is engaged on its opposite faces by the brushes of the receptacle contacts 26 and 27. In this position the blades extend laterally from the nose 70 of the plug through the slots 35 in the sides of the receptacle chambers. When the plug is withdrawn from the receptacle, arcing between the blades and the receptacle contacts is minimized by the constricted blade passages 34 in the top of the contact chamber, through which the blade ends exit.

An important technical advantage results from the location of the contacts of strap 25 at opposite ends of the receptacle. As is well known the outlet box in which a receptacle of the present type is mounted by brackets 130

36—37, is grounded in accordance with the underwriters' requirements. If one of the incoming feed wires is also grounded and the latter be connected to the terminal 19, and thus to strap 25 through screw 23, the contacts 5 27 at opposite ends of the receptacle adjacent the straps 36—37 will have the same polarity as the latter. There will be no tendency therefore for an arc to form between 10 these contacts and the brackets when the plug is withdrawn from the receptacle. The connection of the grounded side of the line to terminal 19 may be indicated by imparting thereto a distinctive color, e. g. white.

15 The receptacle body is extremely simple to manufacture, economical of material, compact in arrangement of contacts, and at the same time provides safe housing and support for the latter as well as reducing danger of 20 arcing on withdrawal of the plug. It will be noted that a duplex receptacle structure is afforded within the area of a receptacle fitting adapted for accommodation in an outlet box of the size commonly used for single 25 outlet fittings.

While the details of construction shown are advantageous, various modifications thereof may be made within the scope of what I claim as my invention.

30 I claim—

1. A plug receptacle comprising an insulating body recessed to form a well with contact chambers on opposite sides thereof, the top walls of said chambers and side walls 35 thereof facing the well being apertured to accommodate entering plug blades.

2. A plug receptacle comprising an insulating body recessed from one face to afford a plug receiving well, and from another 40 face to afford contact chambers on opposite sides of the well, the end wall of said chambers and the side walls thereof facing the well being apertured to accommodate entering plug blades.

45 3. A plug receptacle comprising an insulating body recessed to afford a pair of plug receiving wells, and a pair of contact chambers at opposite sides of each well and laterally opening thereto, together with conducting straps of opposite polarity, each having 50 a pair of associated contacts arranged respectively in the chambers opening to the respective wells.

55 4. A plug receptacle comprising an insulating body recessed to afford a pair of plug receiving wells, and a pair of contact chambers at opposite sides of each well and laterally opening thereto, together with a pair of conductor straps of opposite polarity, each having an associated pair of receptacle 60 contacts, the contacts of one polarity being arranged in chambers intermediate the wells.

65 5. An attachment plug comprising an insulating body of reduced diameter at its entering end, and plug blades the adjacent

edges of which are housed within said end, while their opposite edges project laterally to exposed position at opposite sides thereof.

6. An attachment plug comprising an insulating body recessed to form a wiring chamber, parallel channels extending therefrom to the opposite end of the plug and contact blades in said channels, said channels opening through opposite sides of the entering end of the plug to expose for engagement the edges of the blades lying in said channels and extending beyond the insulating body.

7. An attachment plug comprising complementary blocks of insulating material recessed on their adjacent faces to afford parallel blade receiving channels, said blocks being shouldered to form a nose at the entering end of the plug, the opposite sides of which nose longitudinally intersect the channels to expose the side margins of blades lying in said channels.

8. An attachment plug comprising an insulating body closed at its entering end, but recessed to form interior spaced channels extending into said end and opening laterally to opposite sides thereof, together with blades arranged in said channels and having side and bottom edges projecting laterally beyond the sides of the plug end for engagement with cooperating receptacle contacts.

9. An attachment plug comprising like complementary blocks, recessed on their meeting faces to form at one end an inclosed wiring chamber, and spaced channels leading therefrom to the nose of the plug, contact blades confined in said channels and carrying binding terminals at one end located within the wiring chamber, said blocks being laterally shouldered to expose a portion of the end and one side edge of each of said blades for contact at the nose of the plug.

10. An attachment plug receptacle having contact chambers arranged on opposite sides of a well, the top walls and the side walls of said chambers facing the well being slotted to accommodate the blades of a cooperating plug, together with a plug having an insulating body, the end of which is of reduced dimensions to enter said well, and blades carried by said plug and projecting from opposite sides of said reduced end to pass through the slots of the contact chambers of the receptacle on insertion of the plug into the receptacle.

11. In a multiple receptacle, an insulating body, supporting brackets adapted for connection to a grounded support, contacts adjacent the brackets, terminal means for said contacts, and means indicating the proper connection of said terminal means to the ground side of the feed circuit, together with contacts of opposite polarity arranged on the insulating body at points more remotely

spaced from said supporting brackets than said contacts of ground polarity.

12. A plug receptacle recessed from its face to afford a plug-receiving well with contact chambers at the sides of the well and opening thereto, contacts arranged in said chambers for cooperation with jack blades carried by the plug at its entering end, the top walls of the contact chambers being slotted in register with the contacts to permit the entry of the jack blades into the chambers and into engagement with the receptacle contacts therein.

13. A plug receptacle recessed from its face to afford a plug-receiving well with contact chambers at the sides of the well and opening thereto, contacts arranged in said chambers for cooperation with jack blades carried by the plug at its entering end, the top walls of the contact chambers being slotted in register with the contacts to permit the entry of the jack blades into the chambers and into engagement with the receptacle contacts therein, the side walls of said chambers facing the well being apertured to accommodate the portion of the blade extending between the entering end of the plug and the receptacle contact.

In testimony whereof I have signed my name to this specification.

GILBERT W. GOODRIDGE.
